(57) **CLAIM**

The ornamental design for a duster, as shown and described.

DESCRIPTION

FIG. 1 is a perspective view illustrating my design for a duster;

FIG. 2 is a reduced right side elevation view thereof;

FIG. 3 is a reduced, inverted, left side elevation view thereof;

FIG. 4 is a reduced bottom plan view thereof; and,

FIG. 5 is an enlarged front elevation view thereof.

The fringes are partially shown in FIGS. 2, 3 and 4 for ease of illustration. The broken lines shown in the figures illustrate a handle that could be one environment for the duster and are not part of the claimed design.
